OIL BURNER AND DRAFT CONTROL MECHANISM

Application filed April 16, 1929. Serial No. 355,489.

This invention relates to oil burner draft control mechanism of the automatic type and relates to subject matter disclosed in my application on automatic oil burner steam and draft control, Serial No. 671,813, filed on Oct. 30, 1923.

To efficiently operate steam boilers it is desirable that the boiler pressure be maintained substantially constant. The pressure of steam generated in a boiler is, of course, directly dependent upon the heat generated in the furnace, which, in turn is directly dependent upon the fuel supplied and the draft regulation. The boiler pressure can therefore be automatically regulated by making the fuel supply and draft control mechanism responsive in some manner or other to variations in the boiler pressure. A great many systems of this general nature are now in common use, most of which are directly responsive to boiler pressure variations. However, it has come to my attention that the valves and other mechanism used in controlling the fuel supply and draft regulators are not as sensitive to a small range of variations in high pressure (such as of necessity exist within the boiler) as they are to a wide reduced range of variations in comparatively low pressures. It is therefore desirable that the system include a steam pressure reducing or regulating valve for more efficient operation of the steam atomizing pressure used for atomizing the fuel and controlling the draft regulating mechanisms. It is also desirable in connection with systems of this nature, to utilize a very sensitive draft control mechanism.

In general it is the object of this invention to provide a fuel and draft regulating system responsive to a wide range of variations ranging from a low of 5 pounds to a high of 75 pounds in a reduced pressure steam line.

More specifically the object of the invention is the combination with an oil burner; of a fuel regulator, a draft regulator, a fluid pressure line for operating said fuel and draft regulators, and means for varying the reduced steam atomizing pressure in said

fluid pressure line inversely with respect to the boiler pressure.

Another object of this invention is the provision of sensitive fluid operated draft control mechanism.

The invention possesses other advantageous features, some of which with the foregoing, will be set forth at length in the following description where I shall outline in full that form of my invention which I have selected for illustration in the drawings accompanying and forming part of the present specification. In said drawings, I have shown one form of my invention, but it is to be understood that I do not limit myself to such form, since the invention as set forth in the claims, may be embodied in a plurality of forms.

Referring to the drawings:

Fig. 1 is a diagrammatic representation of a fuel oil burner embodying the objects of my invention.

Fig. 2 is a side elevation of the disclosure made in Fig. 1.

Fig. 3 is a vertical section of the valve used for reducing the boiler pressure and for atomizing the oil fuel.

Fig. 4 is a vertical section of the valve controlled by the reduced atomizing steam pressure and used for regulating the fuel supply to the burner.

Fig. 5 is a vertical section of the draft control mechanism.

Fig. 6 is a horizontal mid-section of the draft control mechanism taken on the plane indicated by the line 6-6 of Fig. 5.

Fig. 7 is a sectional plan view showing the lever and link connection between the pilot valve and the piston rod of the draft regulator, the section being taken on the line 7-7 of Fig. 5.

The invention consists generally of a steam pressure reducing valve 1, a fuel oil regulating valve 2, responsive to the reduced pressure side of the valve 1, and a draft control mechanism 3 also responsive to the reduced steam pressure side of the valve 1. Fuel burners 4 are supplied with fuel by the valve 2, atomized by steam under reduced pressure furnished by the valve 1.

The steam pressure reducing valve 1 consists of two intercommunicating chambers 5 and 6, between which is operatively engaged a rod 7. The upper end of the rod 7 carries valves 8 and 9, while its lower end is clamped in any suitable manner to a diaphragm 11. The valves 8 and 9 are urged in their upward or open position by means of a spring 12 acting through a longitudinally slid able rod 13. 10 As clearly shown in Fig. 3, the tension of the spring 12 is adjustable at will by means of a screw 14.

Inlet and outlet ports 15 and 16 respectively, permit the steam from the boiler to pass 15 through the chamber 5 when the valves 8 and 9 are open, and due to the pressure exerted by the steam on the diaphragm 11, the valves 8 and 9 are correspondingly partially closed, thereby controlling the pressure of the steam 20 passing through the outlet port 16. Since the details of construction of this valve per se, form no part of my invention, it is thought that a further description of its details of construction and operation is unnecessary. 25

The operation and construction of the fuel oil valve 2 is very similar to the construction and operation of the steam pressure reducing valve 1. As shown in Fig. 4, this valve consists, like the valve 1, of two intercommunicating chambers 21 and 22, within which is operatively engaged a rod 23. Secured to the lower end of the rod 23 is a valve member 24 which is urged in its upward or closed position by the action of a spring 25. A screw 26 serves to adjust the tension of this spring as desired. The upper end of the rod 23 indirectly engages a diaphragm 27, which is urged downward to various extents, dependent on the reduced steam pressure entering the intake port 28. Inlet and outlet ports 31 and 32 respectively, permit the fuel oil under pump pressure to enter the valve and to emerge therefrom at a predetermined 40 pressure. This structure of itself, like the valve 1, forms no part of my invention, and therefore has not been described in more detail. 45

The draft control mechanism consists of a cylinder 41 which operatively engages a double acting piston 42 provided with an upwardly extending piston rod 43. Ports 44 and 45 establish communication between a chamber 46, having upper and lower interconnected sections, and the upper and lower ends of the cylinder 41. Slidably disposed within the central portion of the chamber 46 is a rod 47 to which is secured in spaced relation, valve members 48 and 49. As shown in Fig. 5, the valve members 48 and 49 are adapted, in their neutral position, to close the entrances of the ports 44 and 45. In the upper position of the rod 47, communication between the chamber 46 and the port 45 is established. In the lower position of the rod

47, the reverse condition obtains, that is, communication is established between the chamber 46 and the port 44, while communication between the port 45 and the chamber 46 is cut off. An intake conduit 51 is connected with the chamber 46 while an outlet conduit 52 connects with the central portion of the tubular housing 53, within which the valve members 48 and 49 operate. The valves 48 and 49 define, together with the tubular housing 53, a space by which communication may be established between the outlet conduit 52 and either of the ports 44 or 45 depending on whether the rod 47 is in its upper or lower position. 70 75 80

The piston rod 43 extends upwardly through suitable packing and glands provided in the upper end of the cylinder 41, and similarly, the rod 47 extends upwardly through suitable packing and glands in the upper end of the chamber 46. 85

Depending from the lower end of the cylinder 41 is a chamber 54, the upper face of which is formed by a diaphragm 55, while in the lower face thereof, is a port 56 for the admittance of steam under reduced or regulated pressure. Pivotally mounted in a bracket 57 depending from the cylinder 41, is an arm 58, to the outer end of which is pivotally connected a link 59. Engaging the lower surface of the arm 58 intermediate its ends, is a fulcrum 61 which is actuated by the diaphragm 54. Acting downwardly against the upper face of the arm 58 intermediate its outer end and the fulcrum 61, is a spring 62, the tension of which may be adjusted as desired, by a screw 63. Extending upwardly and to the right from the upper end of the cylinder 41 is a bifurcated bracket 65, in the upper end of each branch of said bracket 65 is journaled a stub shaft 65'. The inner ends of the shafts 65' are spaced from each other to slidably accommodate a lever 66 therebetween. The lever 66 is pivoted on an eccentric pin 66' between the adjacent ends of the shafts 65'. The outer end of the lever 66 is in turn pivotally connected to the link 59 while its inner end is pivotally secured to the upper end of the rod 47. A bifurcated link 67 has its branches connected to the shafts 65' on the opposite sides of the lever 66, and it is secured on said shafts 65' by means of set screws 67'. The other end of the link 67 is pivoted to a link 68, which in turn is pivotally connected to a socket 69 mounted on the upper end of the piston rod 43. Thus the lever 66 may be moved around its fulcrum pin 66' independently of the link 67, and is also moved with the piston rod 43 by reason of the rotation of the shafts 65' as the link 67 is swung by the movement of the piston rod 43. The rotation of the shafts 65' causes the eccentric pin 66' to move eccentrically and swing the lever 66 for a compensating pilot valve adjustment. In order to 100 105 110 115 120 125 130

indicate the relative positions of the dampers and air registers, the piston rod 43 is provided with a pointer 71 which is adapted to travel along a calibrated scale 72, secured at its foot 5 to the upper end of the cylinder 41.

The operation of this mechanism is as follows:

Steam under reduced boiler pressure carried by the line 73, enters the chamber 54 forcing the diaphragm 55 upwardly against the fulcrum 61. Due to the upward motion of the fulcrum 61, the outer end of the arm 58 is moved upwardly against the action of the spring 62 thereby forcing the link 59 upwardly and the rod 47 downwardly. The valve member 49 mounted on the rod 47, in moving downwardly establishes communication between the chamber 46 and the upper end of the cylinder 41, while the valve member 48 cuts off communication between the lower end of the cylinder 41 and the chamber 46, as above described. With the valve members 48 and 49 in this position, any suitable working medium, as for example fuel oil, is permitted to enter the chamber 46 through the inlet conduit 51 and to pass through the port 44 into the upper end of the cylinder 41 thereby driving the piston 42 downwardly. In the meantime, the working medium enclosed in the lower end of the cylinder 41 is forced therefrom through the conduit 45 into the space between the two valve members 48 and 49 and out through the conduit 52. When the diaphragm 55 is in its collapsed position, the valve members 48 and 49 are each carried above the outlets of the ports 44 and 45 respectively, thereby establishing communication between the chamber 46 and the lower end of the cylinder 41, and closing 40 communication between the upper end of the cylinder and the chamber 46. With the valve members 48 and 49 in this position, the circuit of the fluid working medium is just reversed from that above described. The working 45 medium enters the chamber 46 and passes into the lower end thereof through the port 45 and into the lower end of the cylinder 41, thereby forcing the piston 42 upwardly. The working medium contained in the upper end 50 of the cylinder 41 is forced through the port 44 into the space contained between the valve members 48 and 49 and hence outwardly through the conduit 52. The motion thus given to the piston 43 is in turn imparted to the linkage or connecting means secured to the socket 69, and transfers a compensating movement to the rod 47 and to the pilot valve of the draft regulator.

As clearly shown in Fig. 1, the pressure reducing valve 1 is placed directly in the steam line from the boiler. Three branch lines 81, 82 and 83 establish communication between the reduced pressure side of the valve 1 and the intake port 28 of the fuel oil regulating valve 2, the port 56 of the draft control mech-

anism 3, and the burners 4 respectively. One of the two branch lines 84 carrying fuel under pressure, communicates with the intake port 31 of the fuel regulating valve 2, while the remaining branch line 84 connects with 70 the intake conduit 51 of the draft control mechanism 3 for operating the piston 42. The exhaust or outlet conduit 52 is of course in communication with the suction side of the fuel pump. After passing through the fuel regulating valve 2, the fuel is supplied by the line 85 to the burners 4 where it is atomized by the steam furnished to the burners by the line 83.

Needless to say, suitable hand operated valves 86 are provided in steam and fuel lines shunted across the valves 1 and 2 respectively, for controlling the entire system by hand in the absence of any steam pressure in the boiler.

Motion from the rod 43 is transmitted by means of links 89 and bell cranks 91 to a stack damper 87 for regulating the opening thereof in accordance with the actuation of the draft control mechanism 3.

The damper regulating linkage is also connected to a link mechanism 92 for opening and closing air registers 88 of ash pits 93. A connecting link 94 extends from the link mechanism 92 to a bell crank lever 95. Upon the bell crank lever 95 is mounted a counter-weight 96 for normally holding the entire linkage in draft opening position. The bell crank lever 95 is connected by a link 97 to an additional damper 98. Another link 99 effects the connection of the bell crank lever 95 to a crank pin 101, the turning of which actuates a link 102, whereby the side draft door 103 is closed or opened. The said link mechanisms are interconnected in such a manner that the draft thru the stack damper 87, air registers 88, additional damper 98, and side draft door 103 is regulated in unison and inversely with respect to the boiler pressure.

Another auxiliary damper 104 is arranged on the top of the boiler and is connected by a link 105 to the bell crank 95, which is also actuated in synchronism with the entire draft control mechanism.

Since both the fuel regulating valve 2 and the draft control mechanism 3 are responsive to a wide range of variations in the reduced pressure from the valve 1, they can be made to operate substantially simultaneously. It is to be noted that the pressure of the steam by which the valve 2 and the draft control mechanism 3 are controlled varies inversely with respect to the boiler pressure.

The control system above described has been found to be very sensitive to a small range of variations in the main steam pressure of the boiler and therefore makes it possible to automatically maintain the boiler pressure substantially constant at all times. In accomplishing this result the draft control

mechanism 3 plays an essential part, for as constructed, it has been found to give a wide range of control and to respond to small pressure increments.

5 I claim:

6 1. In a fuel burning system the combination
7 with steam boilers, of hydrocarbon
8 burners under the boilers, a fuel line to con-
9 duct fuel to the burners, a fuel flow regulator
10 valve interconnected into said fuel line, a
11 draft regulator, a control valve to connect the
12 fuel line to the draft regulator for operating
13 said draft regulator; steam operated means
14 to actuate the fuel flow regulator valve, and
15 steam operated means to actuate said control
16 valve, a steam line to communicate the boiler
17 pressure to both of said steam operated
18 means; and means interconnected in the
19 steam line between the boiler and the said
20 steam operated means to vary the steam
21 pressure in the said line inversely with re-
22 spect to the boiler pressure.

23 2. In a fuel burner system the combination
24 with steam boilers, of hydrocarbon burners
25 operatively related to the boilers, a fuel con-
26 duct to conduct fuel to said burners, a valve
27 connected between the burners and the fuel
28 line to regulate the flow of fuel; a recipro-
29 cating draft regulator, means to connect the
30 draft regulator to the fuel for admitting fuel
31 under pressure to operate said regulator,
32 steam actuated means to operate the first
33 valve; a steam actuated mechanism to oper-
34 ate said draft regulator connecting means,
35 a steam line connected between the boilers
36 and the said steam actuated means and mech-
37 anism; and means interconnected in the
38 steam line to vary the steam pressure in the
39 said line inversely with respect to the boiler
40 pressure.

41 3. In a liquid fuel burner system the combi-
42 nation with steam boilers, of hydrocarbon
43 burners operatively related to the boilers, a
44 fuel line to conduct fuel to said burners, a
45 diaphragm actuated valve to regulate the
46 flow of fuel through the line; a reciprocat-
47 ing draft regulator, a valve to connect the regu-
48 lator to the fuel line to selectively admit fuel
49 under pressure to operate the regulator in
50 opposite directions, a diaphragm actuated
51 mechanism to operate said draft regulator
52 valve, a steam line connected between the
53 boilers and the diaphragms of said fuel valve
54 and of said mechanism; and means intercon-
55 nected into the steam line between the dia-
56 phragms and the boilers to vary steam pres-
57 sure in the said steam line inversely with
58 respect to the boiler pressure.

59 4. In combination with an oil burner to
60 heat boilers, and an oil line conducting oil
61 to the burner, a diaphragm actuated fuel
62 regulator valve interconnected into the oil
63 line, a fluid pressure operated draft regu-
64 lator, a valve to operatively connect the draft
65 regulator to the oil line, a diaphragm actu-

66 ated mechanism to operate said draft regu-
67 lator valve, a fluid pressure line for actuating
68 the diaphragms of the fuel regulator valve
69 and of the said mechanism; and means for
70 automatically varying the pressure in the
71 fluid pressure line inversely with respect to
72 the boiler pressure.

73 5. In combination with an oil burner for
74 boilers, and a fuel line for said burner, a fuel
75 regulator valve interconnected on the fuel
76 line, a diaphragm operator for the valve to
77 close the valve when pressure is decreased on
78 the diaphragm, and to open the valve when
79 pressure is increased on the diaphragm; a
80 fluid pressure operated reciprocating draft
81 regulator, a valve mechanism to connect the
82 fuel line to the respective sides of said oper-
83 ator to move the regulator into draft closing
84 or draft opening positions; a diaphragm to
85 operate the said valve mechanism to reduce
86 the draft when pressure is increased on the
87 diaphragm and to increase the draft when
88 pressure is decreased on the diaphragm, a
89 steam line to connect the boiler to said dia-
90 phragms, and means interconnected into the
91 steam line between the boiler and the said dia-
92 phragms for automatically varying the pres-
93 sure on said diaphragms inversely with re-
94 spect to the boiler pressure.

95 In testimony whereof, I have hereunto set
96 my hand at San Francisco, California, this
97 9th day of April, 1929.

98 EARLE I. STAPLES.
